UNITED STATES PATENT OFFICE.

JOHN H. BUSCHER, OF WASHINGTON, DISTRICT OF COLUMBIA.

PROCESS OF PRODUCING LITHOGRAPHIC INSERTS.

1,347,010.

Specification of Letters Patent.

Patented July 20, 1920.

No Drawing.

Application filed December 4, 1918. Serial No. 265,313.

To all whom it may concern:

Be it known that I, JOHN H. BUSCHER, a citizen of the United States, residing at Washington, District of Columbia, have invented a new and useful Process of Producing Lithographic Inserts, of which the following is a specification.

This invention is a process for producing lithographic inserts of any arbitrary design, 10 and of any preferred selected pattern or ruling, without the use of pattern plates or stones.

In order that the invention may be fully understood by those skilled in the art, it is 15 desirable that the common practice of "pulling" a transfer in the lithographic art, be briefly reviewed. To those familiar with the art it is well known that in order to pull a transfer from a ruling or pattern plate, by 20 the present practice, the paper is first coated with a preparation of starch and flour, which must be permitted to dry. The coating and drying steps require considerable time. The sheet is then dampened with a mixture of 25 glycerin and water, just sufficient to cause it to adhere to the plate, the consistency of the mixture depending upon atmospheric conditions. For instance, on a dry day the mixture must be wetter than on a damp day, and 30 inasmuch as this is a question which depends upon the skill and judgment of the operator, it will be readily understood that considerable time may be wasted before the paper is properly fixed. The next step is to stretch 35 the paper smooth for the plate. The plate must be engraved with all of the consequent trouble of cleaning, and when ready is inked in, wiped off, and polished by wiping, whereupon it is ready to be "pulled." The plate is 40 then put in the press, the paper put on, and pressure applied to force it down into the engraved portions, the plate and paper being then heated and passed through the press the desired number of times, after which the 45 paper is ready to be taken off. As is well-known, if the transfer is pulled with soft ink it is liable to be "squashed," or if pulled with hard ink, it is liable to be too light. In either event, it will have to be pulled over, 50 all of which wastes time and depends wholly upon the skill and judgment of the operator.

To pull a transfer from a pattern or ruling stone, the paper must first be dampened, just the same as for a plate, except that it 55 will probably be dryer for the stone than for the plate. The stone is washed off with

turpentine, and the work having been etched into the stone with acid, only the ink is removed, the stain of the impression remaining. The stone is then rubbed off with ink 60 and gum to give it a body, after which it is rolled up and the impression pulled. The piece of pattern or ruling which is to be put in on the stone must be marked out and gummed around its margin to define the 65 boundaries of a required insert, for instance, and it is then necessary to cut a piece out of the transfer which has just been pulled from the small pattern plate or stone. This insert piece is then put on the marked out and sensitized place of the other stone and run 70 through a press until transferred. This operation depends upon the skill and judgment of the operator, because if it should go down too light or mash out, the transfer 75 must be made all over again, and it is not uncommon to lose an entire day, and if the establishment should not have enough presses, some of the operators will have to wait until a press is free and possibly lose 80 several days.

The object of the present invention is to provide a process by which much time and labor is saved by dispensing with the step of pulling an impression with transfer papers, 85 thereby avoiding the necessity of employing the usual pattern plate or stone, and to apply the insert directly to the sensitized surface of the plate or stone to which the insert is to be applied, by an inked impression member, 90 preferably a roller, containing an impression surface which conforms to the ruling or other ornamental or distinguishing character of the insert.

As is well-known in the art any clean 95 surface on a stone or plate is always "sensitive" i. e., it is of such a character that any ink or grease which touches it will adhere and cannot be removed except by scraping. Therefore it is to be understood that 100 wherever the term "sensitive surface" is referred to in this specification, a clean surface capable of receiving ink is meant. If a supplemental pattern or design is to be placed upon such a clean or sensitive surface 105 and said design is of a particular size to match in with a larger design to show its color, the space where the special supplemental design is to be applied is usually surrounded by a resist and an inked roller 110 is passed over the entire surface of the stone, applying ink not only to the sensitive sur-

face but also to the resist covered surface. After the ink has dried the ink covered resist may be washed off with water leaving undisturbed the space which was intended to 5 receive the ink.

In practising the process of the invention, instead of pulling an impression with transfer paper, a plurality of specially designed rollers are preferably employed, having different designs applied to their peripheries in the form of impression surfaces, each roller having but one design. After the stone has 10 been marked out to define the boundaries of the insert or other portion to be applied, a resist of gum or the like, is placed around the portion surrounding the space where the insert is to be placed, leaving the stone or plate clean and sensitive within said boundaries. The roller having the desired design 15 is then selected, and after being inked in suitable manner, is passed smoothly over the exposed surface not covered by the gum resist, whereupon the pattern or ruling of the roller is directly transferred to the stone or plate upon said exposed sensitive surface, the shade of the impression, either light or dark, manifestly depending upon the pressure applied to the roller in passing it over the stone.

20 From the foregoing it will be readily understood that the transfer paper is entirely dispensed with, as well as the use of small ruling stones or plates, thereby simplifying the lithographic process to a marked degree, 25 and resulting in economy of both time and labor.

I claim as my invention:—

1. A process for producing lithographic inserts comprising marking out a predetermined outline upon a sensitive surface, coat- 30

ing all of said surface except the area defined by said outline, with a resist, and applying a design to the uncoated surface only by means of an inked impression member provided with the desired design. 45

2. A process for producing lithographic inserts comprising marking out a predetermined outline upon a sensitive surface, coating all of said surface except the area defined by said outline, with a resist, and applying a design to the uncoated surface only by a relatively moving impression member 50 provided with the desired design. 50

3. A process for producing lithographic inserts comprising marking out a predetermined outline upon a sensitive surface, coating all of said surface except the area defined by said outline, with a resist, and passing an inked roller over said surface to apply the ink to said outlined area, the periphery of said roller being provided with the desired design. 55

4. A process for producing lithographic inserts comprising rendering a sensitive surface impervious to ink except as to one or more areas of desired contour, and passing an inked impression member over said surface and in contact therewith to apply a design to the exposed areas. 60 65

5. A process for producing lithographic inserts comprising rendering a sensitive surface impervious to ink except as to one or more areas of desired contour, and passing an inked roller over said surface and in contact therewith to apply a design to the exposed area or areas. 70 75

In testimony whereof I have hereunto set my hand.

JOHN H. BUSCHER.
